UNITED STATES PATENT OFFICE.

WILLIAM FONDILLER, OF NEW YORK, N. Y., ASSIGNOR TO WESTERN ELECTRIC COMPANY, INCORPORATED, OF NEW YORK, N. Y., A CORPORATION OF NEW YORK.

LOADING-COIL.

1,210,628.

Specification of Letters Patent.

Patented Jan. 2, 1917.

Application filed June 21, 1916. Serial No. 105,035.

To all whom it may concern:

Be it known that I, WILLIAM FONDILLER, a citizen of the United States, residing at New York, in the county of New York and State of New York, have invented certain new and useful Improvements in Loading-Coils, of which the following is a full, clear, concise, and exact description.

This invention relates to loaded telephone lines, and more particularly it relates to an improved form of loading coil to be used for loading phantom telephone lines. Its object is the reduction of crosstalk in phantom line systems.

It has hitherto been proposed to load a phantom circuit according to the system described in the Campbell and Shaw Patent No. 980,921, by the use of loading coils with discontinuous magnetic cores; that is, cores having small non-magnetic gaps. Such coils have been found effective to minimize to a large extent unbalances in line impedance caused by the magnetizing effect of strong foreign currents, such as lightning discharges, to which the telephone lines may be exposed. A description of such so-called air-gap coils and of their adaptation to the use in question will be found in an application for Letters Patent of Shaw and Fondailler, Serial No. 861,421, filed September 12, 1914.

This invention provides an improved winding arrangement for such air-gap coils, and consists in so proportioning the inner and outer windings of each core section that the mutual inductances between the windings which are in series with one physical circuit and those which are in series with the other physical circuit are balanced, thereby eliminating to a large extent any danger from crosstalk in the coil itself.

The invention will be more clearly understood by reference to the accompanying drawing.

In the drawing, 1 and 2 represent the line conductors of one physical circuit, and 3 and 4 represent the line conductors of another physical circuit which are combined in the usual manner, not here shown, to produce a phantom circuit.

5 is a loading coil with windings connected in series with each one of the four line conductors in such a manner as to add inductance to the phantom circuit without adding inductance to the component physi-

cal circuits. The core of the coil 5 is divided into two sections, each comprising two quadrants, 6 and 9, and 7 and 8, respectively, the sections being separated at their extremities by non-magnetic gaps 10. Each quadrant is provided with an inner and outer winding; for example, quadrant 6 has an inner winding 11 and an outer winding 12; quadrant 7 has an inner winding 13 and an outer winding 14; quadrant 8 has an inner winding 15 and an outer winding 16, and quadrant 9 has an inner winding 17 and an outer winding 18. Each line conductor is connected in series with an outer winding of one quadrant and an inner winding of the opposite quadrant; for example, line conductor 1 is connected to one end of the winding 12, the other end of which is connected to one end of the inner winding 15 on the quadrant 8, the other end of said winding being connected to line again. The windings on the different quadrants are connected in such a way that when phantom circuit currents flow therethrough, the magnetizing effect of the windings will be cumulative to produce a flux in the same circular direction around the core. When physical circuit currents flow, however, the windings of each core quadrant will largely neutralize each other, and only a small resultant flux will be produced.

Considering now the disposition of the windings on the core, it will be noted that there is present a possibility of crosstalk between the two physical circuits in case the mutual inductances between the windings on adjacent core quadrants are not balanced. Considering the windings on any two adjacent quadrants, for example, quadrants 6 and 7, it has been found, where the inner and outer windings have the same number of turns that the mutual inductance of two outer windings, 12 and 14, is greater than the mutual inductance of two inner windings, 11 and 13. It has also been found that the mutual inductance of an inner winding 11 of one quadrant, and an outer winding 14 of an adjacent quadrant is intermediate between the mutual inductance of the two inner windings and the mutual inductance of the two outer windings, but that it is nearer the latter. The same condition obtains with reference to the windings on adjacent quadrants of the same section, such as quadrants 7 and 8, though in this case the absolute

values of the mutual inductances are greater than in the case where the quadrants are separated by an air-gap. The unbalance of mutual inductances thus introduced has been found to be a cause of crosstalk in air-gap coils of the type under consideration.

In the winding arrangement here shown, and which is the feature of novelty herein claimed, the inner windings of the several quadrants are given a slightly greater number of turns than the outer windings, in accordance with an exact and predetermined ratio. The exact ratio to be employed will depend on many factors, such as the size, shape and material of the core and the number and dimensions of the air-gaps. In general, however, a proper balance of the mutual inductances will obtain if the deviation of the mutual inductance between an inner winding of one quadrant and the outer winding of an adjacent quadrant from the mean of the mutual inductance of the two outer windings and the mutual inductance of the two inner windings of said quadrants is the same, in absolute value, regardless of whether these quadrants are separated by air-gaps or not.

A convenient way of realizing this condition is to arrange that this deviation shall be zero, *i. e.*, considering any two adjacent quadrants, the mutual inductance of the inner winding of one quadrant and the outer winding of the other quadrant shall be equal or approximately equal to the mean of the mutual inductance of the two inner and the mutual inductance of the two outer windings.

In a specific case in which this winding arrangement has been applied to a coil for loading a phantom circuit, it has been found that a ratio of 1.03 to 1 has been effective to produce the desired degree of mutual inductance balance in the coil, and to effectively minimize the cross-talk danger.

What is claimed is:

1. A loading coil having a magnetic core, line windings in a plurality of layers on a plurality of sections thereof, some of said sections being separated by non-magnetic gaps, each line conductor through the coil including windings in different layers on opposite core sections, the ratio of turns in said different layers being so proportioned that the mutual inductance between a winding of one layer on one section and a winding of a different layer on an adjacent section shall deviate from the mean of the mutual inductances between two windings of the first layer on said adjacent sections and the two windings of said different layer on said sections, by an amount which shall be the same, in absolute value, regardless of whether said adjacent sections are separated by a non-magnetic gap or not.

2. A loading coil having a magnetic core,

inner and outer windings on a plurality of sections of said core, non-magnetic gaps separating some of said sections, each line conductor through the coil including an inner winding on one core section and an outer winding on the opposite core section, the ratio of turns in said inner and outer windings being such that the deviation of the mutual inductance between an inner winding of one section and an outer winding of an adjacent section from the mean of the mutual inductance of the two inner windings and the mutual inductance of the two outer windings of said sections is the same, in absolute value, regardless of whether said adjacent sections are separated by a non-magnetic gap or not.

3. A loading coil having a magnetic core, line windings in a plurality of layers on a plurality of sections thereof, non-magnetic gaps dividing said sections, each line conductor through the coil including windings in different layers on opposite core sections, the ratio of turns in said different layers being so proportioned that the mutual inductance between the winding of one layer on one section, and the winding of a different layer on an adjacent section shall be equal to the mean of the mutual inductances between the two windings of the first layer on adjacent sections and the two windings of said different layer on said sections.

4. A loading coil having a magnetic core with non-magnetic gaps, inner and outer windings on a plurality of sections of said core, each line conductor through the coil including an inner winding on one core section and an outer winding on the opposite core section, the ratio of turns in said inner and outer windings being so proportioned that the mutual inductance between an inner winding of one section and an outer winding of an adjacent section is midway between the mutual inductance of the two outer windings of adjacent sections and the mutual inductance of the two inner windings of said adjacent sections.

5. In a loaded phantom line system, four line conductors comprising two physical circuits, a loading coil for adding inductance to said line conductors when phantom circuit current flows therein, said coil comprising an annular core, non-magnetic gaps dividing said core into equal sections of two quadrants each, an inner and an outer winding on each quadrant, each line conductor through the coil including an outer winding of one quadrant and an inner winding of the opposite quadrant, the four windings of one physical circuit being located on opposite quadrants, the four windings of the other physical circuit being located on the other two opposite quadrants, the ratio of turns in the inner winding to the turns in the outer windings being greater than unity.

6. In a loaded phantom line system, four line conductors comprising two physical circuits, a loading coil for adding inductance to said line conductors when phantom circuit current flows therein, said coil comprising an annular core, non-magnetic gaps dividing said core into equal sections of two quadrants each, an inner and an outer winding on each quadrant, each line conductor 10 through the coil including an outer winding of one quadrant and an inner winding of the opposite quadrant, the four windings of one physical circuit being located on opposite quadrants; the four windings of the other physical circuit being located on the other two opposite quadrants, the ratio of the number of turns in the inner windings to the number of turns in the outer windings being such that the deviation of the mutual 20 inductance between the inner winding of one quadrant and the outer winding of an adjacent quadrant from the mean of the mutual inductances of the two inner windings and two outer windings of said adjacent quadrants is the same in absolute value regardless of whether said quadrants are on the same or different core sections.
7. In a loaded phantom line system, four line conductors comprising two physical circuits, a loading coil for adding inductance 30 to said line conductors when phantom circuit current flows therein, said coil comprising an annular core, non-magnetic gaps dividing said core into equal sections of two quadrants each, an inner and an outer winding on each quadrant, each line conductor 35 through the coil including an outer winding of one quadrant and an inner winding of the opposite quadrant, the four windings of one physical circuit being located on opposite quadrants, the four windings of the other physical circuit being located on the other two opposite quadrants, the ratio of the number of turns in the inner windings to the number of turns in the outer windings 40 being such that the mutual inductance between an inner winding on one quadrant and an outer winding on an adjacent quadrant is midway between the mutual inductance of the two inner windings and the mutual inductance of the two outer windings 45 of said adjacent quadrants.

In witness whereof, I hereunto subscribe my name this 20th day of June, A. D. 1916.

WILLIAM FONDILLER.
